CHARLES DAVES MATTHEWS, OF NEW ORLEANS, LOUISIANA, ASSIGNOR OF ONE-HALF
TO HENRY E. GUMBEL, OF NEW ORLEANS, LOUISIANA.

THREAD-CUTTING BLADE FOR SEWING-MACHINES.

1,195,834.

Specification of Letters Patent. Patented Aug. 22, 1916.

Application filed August 18, 1915. Serial No. 46,077.

To all whom it may concern:

Be it known that I, CHARLES D. MATTHEWS, a citizen of the United States, and a resident of New Orleans, in the parish of Orleans and State of Louisiana, have invented a new and Improved Thread-Cutting Blade for Sewing-Machines, of which the following is a full, clear, and exact description.

40 This invention relates to a thread cutting attachment for sewing machines and has for its principal object to provide a device of this character which is adapted to be applied to the foot or cloth plate of a sewing machine so as to enable the operator to quickly and conveniently cut the thread and to avoid undue waste of the latter, the cutting device being in the form of a blade which is set into and extends longitudinally of a 15 slot in the plate and is secured to the under side of the latter in any desired manner, with the free end of the cutter disposed above the plate and suitably shaped so that the threads can be engaged under the cutter, 20 which has its lower edge sharpened and inclined at a suitable angle, so that by drawing the thread longitudinally of the cutter the thread will be effectively cut. The shape, angle and length of the cutter may 25 be varied, and its location with respect to the needle may be determined as convenience and efficiency dictates.

For a more complete understanding of the invention reference is to be had to the 35 following description and claims taken in connection with the accompanying drawing, wherein similar characters of reference indicate corresponding parts in all the views, and in which—

40 Figure 1 is a perspective view of a sewing machine showing the thread cutter applied to the cloth plate; Fig. 2 is a plan view of the cutter and the plate to which it is attached; Fig. 3 is a bottom plan view of 45 Fig. 2; Fig. 4 is an enlarged sectional view on the line 4—4, Fig. 1; Fig. 5 is a sectional view on the line 5—5, Fig. 4; Fig. 6 is a perspective view of the cutter or blade detached; Fig. 7 is a bottom plan view of a 50 cloth plate with the thread cutting blade applied in a different manner thereto; and Fig. 8 is a plan view of a throat plate with the cutting blade applied thereto.

Referring to the drawing, A designates 55 the thread cutting attachment, which is

preferably made of a single piece of metal and consists of a vertical blade 1 having at one end a laterally extending attaching base 2 formed with bifurcations 3, and on the free end of the tip of the blade is a laterally projecting lug 4 which is rounded and serves to prevent the material being sewed from catching on the blade, the upper edge of the latter being also rounded at 5 for the same purpose. The bottom edge 6 of the 60 blade is beveled or sharpened and it extends at an angle to the plane of the plate to which it is attached. The length of the blade and the angle of the cutting edge with respect to the length may be varied as desired. 65

The thread cutting device A may be attached to the cloth plate B of a sewing machine, as shown in Fig. 1, or it may be applied to the throat plate C, as shown in Fig. 8. In 70 other words, it may be applied to the right or left of the needle D of the sewing machine, and it is mounted in such a manner that the free end extends rearwardly or away from the operator. The plate to which 75 the cutting device is attached has a slot 7 which is considerably wider than the blade 1, so that there is no danger of dirt accumulating and preventing the effective cutting of the thread. The blade 1 is disposed in a vertical plane and its cutting edge 6 inclines downwardly in a forward direction so that, 80 as the thread is engaged under the tip of the cutter and drawn forwardly toward the operator, the tension on the thread is increased 85 so that the cutting edge will sever the thread. The base portion 2 may be fastened by one of the screws 8 which secure the cleat or retaining member 9 to the plate B, as shown in Figs. 2 to 5 inclusive, but, if desired, the 90 base member 2 may extend in the same direction as the lug 4, as in Fig. 7, and be secured by a separate screw 10, the bifurcations 3 of the base member straddling the screw, as shown. 95

In using the cutter after the sewing is finished, the work is drawn away from the needle so as to pull out the threads a short distance, and then the threads are engaged under the tip of the blade. The operator 100 then draws the work toward her and causes the thread to slip under the cutting edge 6, which, by its angle, causes the tension of the thread to increase, and thereby the cutting edge severs the thread. As the cutting edge 105

is of considerable length it will be effective even after the front or tip portion becomes dull. The blade is suitably spaced from the needle D and presser foot E, so that after 5 the threads are cut the ends will be of sufficient length to be ready for the next sewing operation.

Although the cutter is shown in the cloth and throat plate of the machine it is to be 10 understood that it may be mounted at a convenient point in the bed plate F, if desired.

From the foregoing description taken in connection with the accompanying drawing, the advantages of the construction and 15 method of operation will be readily understood by those skilled in the art to which the invention appertains, and while I have described the principle of operation, together with the device which I now consider to be 20 the best embodiment thereof, I desire to have it understood that the device shown is merely illustrative and that such changes may be made when desired as fall within the scope of the appended claims.

25 Having thus described my invention, I claim as new and desire to secure by Letters Patent:

1. In a sewing machine, the combination of a needle and presser foot, with a plate 30 associated therewith and having a slot, a thread cutting blade extending longitudinally of and fixed in the slot and having its bottom edge inclined downwardly and sharpened, the tip of the blade extending 35 permanently out of the slot at one end and provided with a flat horizontal lug lying

slightly above the plate to permit a thread to be engaged under the blade while preventing work from being caught on the latter, the opposite end of the blade being secured 40 to the plate.

2. In a sewing machine, the combination of a needle and presser foot, with a member on which the work is supported, said member having a slot, and a thread cutting blade 45 mounted in the slot, one end of the blade being disposed above the slot and formed with a flat horizontal lug to prevent the work from catching on the blade, the base end of the blade being provided with an anchoring 50 member, and the bottom edge of the blade being inclined and sharpened, whereby the thread engaged under the blade can be cut by being drawn longitudinally of the blade.

3. A thread cutting attachment of the 55 class described, comprising a vertical blade having a downwardly inclined bottom cutting edge, a laterally projecting anchoring member on the base end of the blade, and a flat horizontal guard member on the tip end 60 of the blade and extending laterally therefrom and rounded for preventing the work from being caught thereon, the cutting edge inclining upwardly from the base end of the 65 blade to the tip.

In testimony whereof I have signed my name to this specification in the presence of two subscribing witnesses.

CHARLES DAVES MATTHEWS.
